(**) Term: **14 Years**

(57) **CLAIM**

(21) Appl. No.: **29/171,567**

The ornamental design for a remote control device, as shown and described.

(22) Filed: **Nov. 21, 2002**

DESCRIPTION

Related U.S. Application Data

(63) Continuation of application No. 29/158,204, filed on Mar. 29, 2002.
(51) **LOC (7) Cl.** **14-03**
(52) **U.S. Cl.** **D14/218**
(58) **Field of Search** D14/174, 217, D14/218, 137-139, 151, 191-193, 124, 299, 167-168; D13/168, 162-164; D21/512-517, 566; D10/104, 106; 455/352-355, 151.1-151.4; 348/114, 734

FIG. 1 is a perspective view of a remote control device;
FIG. 2 is a front elevational view thereof;
FIG. 3 is a right side elevational view thereof;
FIG. 4 is a left side elevational view thereof;
FIG. 5 is a rear elevational view thereof;
FIG. 6 is a top plan view thereof; and,
FIG. 7 is a bottom plan view thereof.
